CLAIM

We claim the ornamental design for a case for data transmitting devices, as shown and described.

DESCRIPTION

FIG. 1 is a top left perspective view of a case for data transmitting devices of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a top right perspective view; and,

FIG. 9 is a top left perspective view thereof with the flap opened.

The broken lines in the drawings represent portions of the case for data transmitting devices that form no part of the claimed design. Additionally, the dash-dot-dashed lines in the drawings define the boundaries of the claimed design.
